Filed Jan. 22, 1930

UNITED STATES PATENT OFFICE

MARY G. SYKORA, OF DES MOINES, IOWA

WEARING APPAREL

Application filed January 22, 1930. Serial No. 422,599.

This invention relates broadly to wearing apparel, and has more particular reference to a hat.

The primary object of this invention is therefore to provide a hat which can be constructed from a single blank of material, and which in its final phase of construction provides for a combined hat and neck scarf.

A still further object of the invention is to provide a hat of the above mentioned character, that is easily adjustable to fit heads of varying size.

Other objects and advantages of the invention will become apparent from a study of the following description, taken in connection with the accompanying drawings wherein:

Figure 1 is a side elevational view of a hat embodying the features of the present invention.

Figure 2 is a plan view of the blank from which the hat is formed.

Figure 3 is a perspective view of the hat, the neck scarf portion of the same being shown rolled to one side for clearly illustrating certain features of the invention.

Figure 4 is a fragmentary view of a portion of the hat at the inside thereof for showing the pocket accommodating the elastic strip forming part of the adjusting means.

Figure 5 is a fragmentary detail sectional elevational view of a portion of the hat for clearly illustrating the adjustable means therefor.

Figure 6 is a detail sectional view taken substantially on the line 6-6 of Figure 5.

Figure 7 is a plan view of an elastic strip forming parts of the invention.

Referring more in detail to the drawings, it will be seen that the hat is designated generally by the reference character 41, and the same is formed from a single blank of material, such as felt, silk or other suitable material, suitably cut and shaped to provide a relatively narrow elongated portion 42 tapering toward one end, and having one longitudinal edge thereof relatively straight and the other longitudinal edge thereof cut in somewhat of a zig-zag manner.

At that end remote from the tapered end

of the portion 42, the blank is provided with a portion 60 which forms a continuation of the portion 42 and the portions 42 and 60 are rolled, and the curved edge of the portion 60 is stitched to the tapered end of the portion 42 as at 60a as shown in Figure 3. At the junction of the portions 42 and 60, the blank is provided with a projecting portion 46 which is stitched to the edge 43 of the portion 42 as at 43a, the projection 46 thus providing the crown of the hat. In stitching the edge 43 to the edge of the portion 46 the portion 42 adjacent said edge is gathered as suggested in dotted lines in Figure 2 and more clearly shown in Figure 3.

From what has been hereinbefore stated, it will be seen that the hat so provided is rimless and is of the type known in the art as a "turban".

The portion 42 of the blank adjacent its zig-zag edge, is folded upon itself on a substantially zig-zag fold line 44 beginning from a point intermediate the ends of the portion 42 and continuing to the tapered end of said portion 42 as shown in Figure 2. Thus is provided portions 44' folded over the body of the portion 42 at the outer face thereof which provides for a neat and attractive edge portion for the hat at the front thereof.

The portion 42 at that end thereof adjacent the portion 60 forms a part of the back of the hat, and at the zig-zag edge thereof is provided with buttons or other ornamentalations 59. The muffler or neck scarf forming part or extension 45 on one edge thereof is provided with relatively spaced series of button engaging loops 62 for engaging the buttons 59 for retaining a portion of the scarf forming part 45 in proper position at the rear of the hat, it being noted that the scarf extends rearwardly with respect to the hat and is adapted to be passed about the throat or neck of the wearer in a manner conventional to neck scarfs.

Adjacent its opposite edge the neck scarf forming part 45 is provided with spaced series of buttons 61 which add weight to the scarf forming part so that the same will lie neatly when folded or passed around the neck of the wearer.

From a study of Figure 2, it will be noted that at the tapered end of the part 42 there is provided a projection 62a, and this projection 62a passes to the inner side of the portion 60 when the hat has assumed the shape shown in Figure 3 and is stitched or otherwise secured to the corresponding parts of the portion 60.

The extension 62a has an edge portion 62b folded and stitched to the extension 62a as clearly suggested in Figures 4 to 6 inclusive to provide an open ended pocket to the side and slightly rearwardly of the hat for accommodating an elastic-adjusting band 63. Adjacent one end of the pocket there is provided a series of relatively spaced eyes 66. Adjacent the relatively opposite end of the pocket there is a single eye 65. At each end thereof, the elastic-adjusting strip 63 is provided with a hook 64. The hook 64 at one end of the strip is engageable with the single eye 65, while the hook 64 at the relatively opposite end of the strip is engageable with a selected one of the series of eyes 66 according to the desired adjustment.

Means is also provided to prevent total displacement of strip 63, and such means comprises a suitable length of cord 67 that is first passed through the single eye 65 at one end of the pocket, and then subsequently secured at its ends to a proximate end of the adjusting strip 63. A similar length of cord 67 is also passed through a selected one of the series of eyes 66 and then has its ends secured to a proximate end of the strip 63.

Thus it will be seen that while the strip 63 is held against total displacement, it may be readily extended or contracted as required for effecting the desired adjustment of the size of the hat.

As shown in Figure 3, at the front of the hat there may be provided suitable ornamentalations as suggested by broken lines to enhance the attractive appearance of the hat.

Even though I have herein shown and described the preferred embodiment of the invention, it is to be understood that the same is susceptible of changes, modifications and improvements coming within the spirit of the invention as herein described and the scope of the appended claims.

Having thus described my invention, what I claim as new is:

1. A hat formed from a single length of material including a part shaped to constitute a head covering, together with an elongated extension part constituting a muffler, and means carried by the first mentioned part for adjusting the head covering formed thereby, said means including a pocket, an elastic member arranged in the pocket, fixed eyes arranged adjacent opposite ends of the pocket, and hooks on relatively opposite ends of the elastic member engaged with said eyes.
2. A hat formed from a single elongated

strip of material including a relatively wide elongated end portion wrapped "turban fashion" to form the body of the hat, and a relatively narrow elongated end portion constituting a muffler and adapted to be wrapped about the neck of the wearer, the intermediate portion of said strip being provided with an extension having an edge portion stitched to a proximate edge of the first mentioned end portion of said strip and constituting the crown portion of the hat.

3. A hat formed from a single blank of material suitably cut and shaped to provide a head covering portion and a muffler portion integral with the head covering portion at one side thereof, said head covering portion and said muffler portion provided with complementary means for retaining the muffler portion wrapped about the neck of the wearer, and means internally of the head covering portion of the hat for adjusting the size thereof.

4. A hat comprising a body or head covering portion, a pocket within said head covering portion, fixed eyes arranged adjacent the ends of the said pocket, an elastic member arranged in the pocket, hooks on the elastic member engageable with said eyes, and substantially non-elastic means connecting said elastic member with certain of the eyes whereby the elastic member is retained in the said pocket against total displacement.

In testimony whereof I affix my signature.

MARY G. SYKORA.
